UNITED STATES PATENT OFFICE.

JESSE C. KANE, OF EASTON, PENNSYLVANIA, ASSIGNOR TO CHIPMAN KNITTING MILLS, OF EASTON, PENNSYLVANIA, A CORPORATION OF PENNSYLVANIA.

KNITTING MACHINE.

Application filed April 26, 1923. Serial No. 634,656.

To all whom it may concern:

Be it known that I, JESSE C. KANE, a citizen of the United States, residing at Easton, in the county of Northampton and State of Pennsylvania, have invented certain new and useful Improvements in Knitting Machines, of which the following is a specification, reference being had to the accompanying drawings.

10 My invention relates generally to knitting machines, and is more specifically directed to improvements, upon such machines for facilitating feeding of yarn to them.

As is well known in connection with the 15 operation of knitting machines, the feeding of yarns knotted, burred, or even those constituted of curly or kinky fibers, such for example as wool or worsted yarn, is always attended by the possibility of production of 20 tuck stitches or fracture as a result of being detained or caught in the needle hooks, or in the notches or throats of the web holders ordinarily provided to cooperate with them. The fabric produced on the one hand 25 is therefore imperfect and at best can be disposed of only at a loss, and, on the other hand, pressed off the needles entailing loss of considerable time necessitated for re-threading of the machines and initiating 30 starting of the threads on the needles.

The primary object of my invention is to overcome the difficulties referred to so that the possibility of their occurrence is reduced to a minimum.

35 How this desideratum may be attained, together with other objects and attendant advantages, will be readily understood from the detailed description which follows of a typical embodiment of my invention, while 40 the appended claims clearly define the scope of the invention in so far as it comes within my present knowledge.

Referring to the drawings, Fig. I is an 45 illustration in cross-sectional elevation, of the knitting head of a circular or rotary stocking machine convenient for the purposes of my invention.

Fig. II is a partial plan section through 50 the web holder ring taken as indicated by the arrows II-II in Fig. I.

Fig. III is an illustration, more or less diagrammatically showing a partial linear development of the cams by which the knitting needles are actuated; and

55 Figs. IV and V are detail views illustrat-

ing two different relative positions assumed by the needles and web holders in accordance with my invention.

In these illustrations, the needle cylinder indicated at 1 is shown as provided with the usual longitudinally extending, peripheral grooves 2 for vertical guidance of the needles 3. This needle cylinder 1, it will be observed, is mounted upon a bevel gear 4 supported in a recess 5 of a bed plate 6 and designed to be either rotated or oscillated by any approved means, (not shown), such as ordinarily provided in standard types of knitting machines for this purpose.

The machine is further equipped with a 70 needle latch-guard ring 7 which overhangs the top of the needle cylinder 1, said ring being pivoted at 8, to an upstanding post 9 bolted or otherwise secured to the bed plate 6 so that it may be readily withdrawn when 75 access must be had to the needles 3. The latch guard ring 7 carries the usual series of interchangeable pivoted yarn feeds 10 adapted to be individually actuated, from an appropriate pattern control, through the 80 instrumentality of interposed thrust bars such as indicated at 11.

As best seen in Figure III of the drawings the cams which actuate the needles include the common type of upper and lower 85 center cams 12, 13 these being flanked at opposite sides by the stitch cams 14, 14 each of which, in accordance with my invention, are characterized by provision of sharply defined recesses 15 in their relatively remote 90 inclined edges 16, directly adjacent the bottom corners 17. By virtue of this provision, the needles 3 immediately after drawing loops or stitches, are suddenly released from the influence of the cams 14 for a purpose which 95 will be fully explained in detail later herein.

Stitch formation is effected with the assistance of web holders 20, which are retained and guided for horizontal reciprocation relative to the needles 3, in radial 100 slots or grooves of an annulus or ring 21 secured about the top of the needle cylinder 1. As will be apparent from Figs. IV and V of the drawings, these web holders 20 are of standard design in that they comprise the 105 usual web engaging notches or throats 22 with overhanging nibs 23, and at their opposite ends, upstanding butts 24. A cap ring 25 superposed upon the ring 21, carries the cams whereby the web holders 20 are actu- 110

ated. These cams, it will be noted from Fig. II, include a center retracting cam 26 and projecting cams 27, 27, one disposed at each side of said center cam, the group co-operating to cause a deviation at the region of stitch formation from the normal course determined by the concentric groove 28 which occupies the greater portion of the ring 25. Attention is particularly directed to the fact 10 that the receding edges 29 of the center cam 26 are interrupted at the ends of the latter, by protuberances or projections 30, 30 and the edges of the flanking cams 27 recessed as at 31, 31 directly opposite said protuberances or projections. The institution of the special features just noted results in additional, though lesser retractions from the normal course of the web holders 20, these retractions occurring immediately after 20 stitch formation and concurrently with the release of the needles 3 as hereinbefore noted.

The operation of the machine herein shown is, in general, after a manner well known to those skilled in the knitting arts 25 and need not therefore be recited in detail herein, but it is thought expedient to point out in this connection, that my invention is operative both in rotary and oscillatory knitting. With reference to Fig. III of the drawings, it will be noted that the yarn indicated by the letter "Y" is directed at a declination from the yarn feed 10 toward the point of stitch formation at "P" approximating the downward slope of the 30 needles 3 determined by that cam 14 which is active. The drawing of the loops is consequent upon the passing of the needle butts beneath the lower corner 17 of the cam 14, the web holders 20 being at this time projected along the line IV—IV in Fig. II and the relation existing between the needles 3 and the web holders 20 that suggested in Fig. IV, with the loops under maximum tension. However, immediately after the 35 needle butts pass the lower corner 17 of the cam 14, they are suddenly released with the result that the pull on the previously formed loop is relaxed, this, as before hinted, occurring concurrently with the retraction of 40 the corresponding web holder 20 by the protuberance or projection 30 of the web holder retracting cam 26 along the line V—V in Fig. II. In being released, as explained, the needles 3 rise slightly under relaxation of 45 the loops when the relation with the web holders 20 is that suggested in Fig. V, with the needle hooks, or rather the bights of the

needle hooks substantially in registry with the notches or throats 22 of said web holders. It is important to note at this juncture, that 60 the second or additional retraction of the web holders 20 for the special purpose of my invention, is somewhat less than that of the usual or normal retraction necessary in stitch formation so that a slight overlap 65 is caused to exist between their overhang nibs 23 and the hooks of the needles 3, as clearly shown in Fig. V, to avoid release of the web; but in this way, I gain the advantage of a larger space through which the yarn 70 Y may readily reeve with easement for the passage of knots, burrs or other enlargements therein. Moreover, the relaxation in the pull upon the yarn Y as now well understood from what has already been said, 75 permits compensative tensional adjustment between the loop being formed and its immediate predecessor, which will obviously further assist in the easement of yarn feeding and thereby in turn reduce the possibility of rupture due to knots or burrs in the yarn to an absolute minimum.

Having thus described my invention, I claim:

1. In a knitting machine, the combination of needles, web holders co-operating with the needles, and means whereby the needles are released and the web holders simultaneously retracted immediately after formation of a fabric loop to facilitate drawing of a loop by the next succeeding needle. 85

2. In a knitting machine, the combination of needles, web holders co-operating with the needles, a center-retracting cam having protuberances at the ends thereof, 95 and flanking cams having recesses opposed to said protuberances whereby the needles are released and the web holders simultaneously retracted immediately after formation of a fabric loop to facilitate drawing 100 of the succeeding loop.

3. In a knitting machine, the combination of needles, web holders co-operating with the needles, and center-retracting with flank-projecting cams whereby the needles are released and the web holders simultaneously retracted immediately after formation of a fabric loop to facilitate drawing of a 105 loop by the next succeeding needle.

In testimony whereof, I have hereunto signed my name at Easton, Pennsylvania this 19th day of April 1923.

JESSE C. KANE.
